(57) **CLAIM**

The ornamental design for a rim for furniture, as shown and described.

DESCRIPTION

FIG. 1 is a perspective view of the rim for furniture showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The rim for furniture is shown with a symbolic break in its length. The appearance of any portion of the article between the break lines forms no part of the claimed design.
